UNITED STATES PATENT OFFICE.

CHARLES POTTER, JR., OF WESTERLY, RHODE ISLAND.

OSCILLATING PRINTING-PRESS.

Specification of Letters Patent No. 17,449, dated June 2, 1857.

To all whom it may concern:

Be it known that I, CHARLES POTTER, Jr., of Westerly, county of Washington, and State of Rhode Island, have invented certain new and useful Improvements in Oscillating Printing-Presses; and I do declare the following to be a true and exact description thereof, reference being had to the accompanying drawings, in which—

10 Figure 1, is a perspective view; Fig. 2, a vertical section showing the parts in position for receiving the sheet; Fig. 3, a section showing the parts in position after having delivered the sheet; and Fig. 4, an elevation 15 of the "fly," the same letters referring to like parts in all the figures.

My invention consists in an improved method of regulating the impression, and also of feeding in and throwing out the 20 sheets, and is applicable particularly to the press patented by Merwin Davis July 24th 1855.

The main features of the press are similar to those described in said Davis' patent 25 and in the drawings are represented as follows, viz: A, is the frame work of suitable shape to contain the parts; B, is the bed attached to the column B' and made to oscillate from the center b by means of the 30 crank c and connection c'. D is the eccentric segment which gives the impression, operated by its pinion d, lever e, and the cam f. The inking apparatus is that described in 35 said Davis' specification and is not represented in the drawings.

The arrangement for adjusting the impression is constructed as follows: There is a shaft g extending across the frame and supporting at each end a lever h, which is 40 loose upon said shaft. These levers are of the second class, having their fulcra on the shaft g and supporting the bed B by its bearings b while the long arms of said levers are made adjustable by means of the screws 45 i and hand wheels k. Screws i have their bearings upon lugs cast upon the frame. The advantages of this method are obvious—viz., an easy, convenient and rapid adjustment of the impression, perfectly firm, not liable to get out of order, and not interfering with the proper action of the gears d and e Fig. 1.

In Mr. Davis' arrangement the sheets are fed to the grippers by a sliding finger-board to which they are placed by the person feeding. More than a year's experience

in the use of these machines, has demonstrated among others the three following very serious objections to this mode, viz: The impossibility of getting a good "register," much difficulty in inserting the sheets under the fingers and liability to derangement. All these objections are removed by my improved feeding apparatus which is as follows: The feed board l extends inward 60 to a point where it will clear the most prominent points of the bed and segment as they oscillate. At its inward end is an adjustable strip m, extending a little above its surface and serving as a guide for placing the sheets. Near its middle the feedboard is hinged and the lower portion is capable of being lifted upward a short distance by means of levers n and n' on shaft o operated by the cam p on the crank shaft through 65 lever p' and connection p."

The manner of operation is as follows: The sheet being laid on the feed board to guide m or adjusted by "points" or other convenient method, as the segment D comes to the position shown in Fig. 2 the cam p operating through its levers raises the feed board until it nearly touches the segment, when it comes in contact with a toe r on the gripper shaft and shuts the grippers onto 70 the sheet, when the sheet is drawn in and impressed while the feed board recedes to its former position ready to receive another sheet.

In the arrangement described by Mr. 75 Davis in his specification, the fly was attached to the column supporting the bed and had two motions, a vibration on its own axis and an oscillation in connection with the column to which it was attached. The objection to this method is the sheets are not laid evenly the place of deposit varying with every change of speed and at a slow speed the sheets would drop upon the floor, the resistance of the atmosphere not being sufficient to hold them against the "fly." In my improved arrangement this objection is entirely obviated and the sheets are deposited evenly at all speeds. I make the "fly" in the peculiar form represented in 80 Fig. 4, and attach it to the sides of the frame entirely independent of the bed or column. While the impression is being given the "fly" is drawn up into position by means of the cam s (Fig. 3) through its lever t and connection t'. When it arrives at 85 the proper point for receiving the sheet it

- remains stationary while the sheet slides down upon it, then it follows the sheet forward until the segment or platen D arrives at the point shown in Fig. 3, when a toe 5 upon the gripper shaft strikes the stop or tripper *u* and releases the sheet; at this moment the cam *s* lets go of the "fly" and the spring *b* forces it down carrying the sheet to the flyboard *w*. It will be seen that 10 as the "fly" is thrown by a spring it will perform its downward motion always in the same time without reference to the speed of the press which insures the merits above mentioned.
- 15 As the foregoing objections have been fully and practically tested, so has the value of what I claim as my improvements been thoroughly demonstrated on presses of full size.
- 20 I do not wish to be understood as laying claim to any part of the invention of said Davis; neither do I claim lifting the feed-board for the purpose of carrying the sheet

to the grippers independent of its application or adaptation as herein described; 25 neither do I claim actuating the "fly" by a cam and spring as that is common, but

What I do claim and desire to secure by Letters Patent is—

1. The manner of adjusting the impression 30 by means of the levers *h* and screws *i* substantially as described.
2. I claim the use and adaptation of the lifting feedboard *l* for carrying the sheet to the grippers, when combined with the 35 oscillating eccentric segment D.
3. I also claim operating the "fly" by the cam *s* when so constructed as to cause said "fly" to conform to the motions of the bed B and oscillating eccentric segment D as 40 above fully set forth.

CHARLES POTTER, JR.
